UNITED STATES PATENT OFFICE.

ALMOR M. PUCKETT, OF SAN ANTONIO, TEXAS.

SIGNAL-LAMP FOR VEHICLES.

1,003,949.

Specification of Letters Patent. Patented Sept. 19, 1911.

Original application filed December 1, 1910, Serial No. 595,146. Divided and this application filed May 25, 1911. Serial No. 629,429.

To all whom it may concern:

Be it known that I, ALMOR M. PUCKETT, a citizen of the United States, residing at San Antonio, in the county of Bexar and 5 State of Texas, have invented certain new and useful Improvements in Signal-Lamps for Vehicles; and I do declare the following to be a full, clear, and exact description of the invention, such as will enable others 10 skilled in the art to which it appertains to make and use the same.

This invention relates to improvements in combined signal and number displaying lamps for vehicles and is a division of my 15 application Serial No. 595,146 filed December 1, 1910, for a combined signal and sign displaying lamp for vehicles.

The object of the invention is to provide a lamp of this character the casing of 20 which is so arranged that but one light is required for illuminating the rear and side signals and the sign or number.

With the foregoing and other objects in view the invention consists of certain novel 25 features of construction, combination and arrangement of parts as will be more fully described and particularly pointed out in the appended claim.

In the accompanying drawings, Figure 30 1 represents a rear elevation of a lamp constructed in accordance with this invention. Fig. 2 is an enlarged central vertical sectional view thereof. Fig. 3 is a vertical sectional view through the lamp on the line 35 3—3 of Fig. 2.

In the embodiment illustrated a lamp is shown having a body portion 1 which may be constructed of any suitable material and of any desired form being here shown cylindrical at its upper and lower ends and of 40 globular form between its ends. The upper end of the body portion is closed by a hinged top comprising an inner tube 2 having on its upper end a shield or cap 3 which is spaced a slight distance above the upper 45 end of the tube and is secured to said end by lugs 4. In the tube near its lower portion is formed a series of ventilating passages 5 around which and spaced a suitable 50 distance from the outer side of the inner tube is an outer tube 6, said outer tube having its upper end covered and protected by a cap 7. On the lower end of the outer tube 6 is secured an annular flange 9 which 55 is adapted to fit the upper end of the body

1 and is hingedly connected thereto to permit the top to be swung back to an open position when desired. At a suitable position on the top is arranged a spring catch 10 whereby the top is held in closed position. 60

One side of the globular portion of the body 1 is cut out and in the opening thus formed is secured the inner end of a sign supporting and display box 11, which may 65 be of any suitable or desired construction, being herein shown triangular in cross section and provided with a suitable view opening 12 and with an opening in its inner end for a purpose to be described. 70

In one side of the globular portion of the body 1 is arranged a rearwardly projecting light conducting tube 28, said tube being disposed immediately below the center of the box 11 and having arranged on its rear 75 or outer end an annular head 29 in which is secured a red glass signal lens 30 through which a red light is displayed at the rear of the vehicle. On another side of the body portion 1 and in the same horizontal plane 80 as the tube 28 is a laterally projecting light conducting tube 31 arranged at right angles to the tube 28. This tube 31 is provided on its outer end with a head 32 in which is secured a green glass lens 33 for the side 85 signal light.

Detachably secured to the lower end of the body portion 1 of the lamp is a lamp socket or receptacle 34 which may be of any suitable or desired form and in which 90 is arranged a lamp 40 of any desired construction.

In the body portion 1 behind the flame of the lamp 40 is arranged a reflector 46 which together with the polished inner surface of the sign display box 11 throws the light of the lamp 40 through the signal tubes 28 and 31 and on the sign in the box 11, the light passing through the open rear or inner end of the box 11. 100

Any suitable means may be provided for supporting the lamp in position on the rear of a vehicle a socket 45 being herein shown for this purpose.

From the foregoing description taken in 105 connection with the accompanying drawings, the construction and operation of the invention will be readily understood without requiring a more extended explanation.

Various changes in the form, proportion 110

and the minor details of construction may be resorted to without departing from the principle or sacrificing any of the advantages of the invention as defined in the appended claim.

I claim as my invention -

A lamp comprising a body, a reflector arranged therein, a sign holding box having an open side disposed opposite said reflector, and light conducting tubes extending from the body at right angles to each other

and arranged in the same horizontal plane, said tubes being disposed below said box and one of them arranged opposite said reflector.

In testimony whereof I have hereunto set my hand in presence of two subscribing witnesses.

ALMOR M. PUCKETT.
